KNOCKDOWN CHAIR

Theodore F. Debski, Brooklyn, N. Y.

Application January 25, 1950, Serial No. 140,389

1 Claim. (Cl. 155—196)

1

This invention is an improved article of furniture, and more particularly an article of furniture comprising several unitary members constituting the principal parts, all joined together with each in its proper place.

An important object of my invention is to provide an article of furniture made of parts that can be easily assembled and detached from one another, and so constructed that the weight of the parts insures their continued union and any additional weight on the article acts to make the connection more secure so long as the article remains set up for use.

A further object is to provide an article of furniture with its members united at the corners, said members being designed to be joined by moving the parts in a predetermined manner to assemble them; and in the reverse manner to separate them.

The nature and advantages of the invention are set forth in the ensuing description and the novel features are defined in the appended claim. The drawings illustrate a preferred form of my invention, but changes in structural details can of course be adopted without departure from the general plan by which the invention is distinguished.

On the drawings:

Figure 1 is an elevation of the back frame or member.

Figure 2 is an elevation showing the shape of the side members.

Figure 3 is an elevation of the front member.

Figure 4 is a top plan of the seat frame.

Figure 5 is an isometric view of the completed chair; and

Figure 6 shows a detail, in section on line 6—6 of Figure 5.

The invention is presented as embodied in a chair, but it may have the form of a sofa or other article and still contain the same characteristics.

The chair as shown comprises a back 1, front 2, sides 3 and frame 4 to bear the seat. These members are preferably of open framework, braced to make them strong and rigid throughout. The back member has uprights 5, joined by a top piece 6, and cross pieces 7 near the lower part; the upper cross piece being united to the top 6 by vertical braces 8. The side members 3 have uprights or legs 9 at the rear, and pieces 10 joined to the posts 9 at one end to make the horizontal arms for the sides, and bent down to make uprights or posts at the front. The vertical portions of the pieces 10 and the uprights

2

9 are braced by cross bars 11. The front 2 has uprights 12 connected by a bar 13 at the upper ends and a cross bar 7.

The back 1 has projections in the form of metal studs or pins 14 projecting sidewise from the posts 5. These studs are one near the top and the other just below the upper crosspiece 7. They are inclined downward and both are preferably in the plane of the framework 1. In the sides 10 of the legs 9 of the frames 3 are matching holes or bores 15 to receive the studs 14. These bores are also inclined downward and the planes containing them are substantially perpendicular to the frames 3. The back and sides are assembled 15 by lifting the former until the ends of the studs 14 register with the holes 15 and then pushing the back down until the studs 14 are fully within the bores 15. These members can then be disconnected not by lateral movement, but only by 20 movement of one or the other diagonally with respect to the height of this chair.

The front 2 has similar inclined studs 14 projecting sidewise from the posts 12 to enter inclined bores 14 at the inner sides of the uprights 25 formed by the front parts of the pieces 10 of the sides 3. Hence the front and sides can be joined in the same way as the back and sides and all four members be assembled without tools and firmly joined together; and can only be separated 30 by lifting the top and front, or depressing the sides, and giving said members relative motion sidewise away from the positions they fill when joined to one another.

The top bar 13 of the front and the upper bar 35 7 and 11 in the back and sides are in the same level and the seat frame 4 is of a size to fit within the space encompassed by these bars. The frame 4 has studs 16 at its forward edge projecting out at right angles to be pushed into holes 17 in the top bar 13 of the front 2; and the rear portions of the upper bars 11 of the sides 3 have openings 18 in line with openings 19 in the frame 4. Suitable bolts 20 are pushed through these openings and secured by nuts to hold the frame 4 in place. 40 Also the posts 5 and 9 have registering holes 21 near their lower ends to receive a long rod 22 to be engaged by a nut on its end to make the parts fast at these points also. A similar rod can be used instead of the separate small bolts 20. The 45 bolts 20 and rod 21 lock all the frames in assembled relation.

The design thus lends itself very nicely to the building of a chair or other article, especially of rattan or other rods, though the invention is not 50 limited to such material or to the form or shape

of a chair, as it may be embodied in other forms having the same general design.

The chair or like can be easily and inexpensively produced and readily set up or taken down. The only tool needed is a small wrench to remove the nuts on the parts 20 and 21, and not even a wrench is required if wing nuts are utilized.

The lower ends of the posts 9 may be inclined backward somewhat just below the rod 22 to give the chair greater stability; but the lower ends of the posts 9 may be bent rearward beginning at any other convenient point, such as the junction of the posts 9 with the upper bars 11. Also the upper parts of the posts 9 can be bent back, together with the posts 5 and braces 8, beginning 15 at any convenient point.

The studs 14 at each side of the back frame 1 and forward frame 2 must of course be parallel to each other and more than two studs may be used if desired. The bolts 20 are carriage bolts with oval heads and square shoulders, and the nuts 20 should preferably be wing nuts, to be readily tightened by hand without a tool of any kind. The rod 22 can of course be replaced by bolts and wing nuts to secure the back and side frames together.

Also the upper bars 11 can slant rearward towards the ends of the lower bars 7. The seat frame 4 will then be inclined slightly towards the back of the chair.

Having described my invention, what I believe to be new is:

A support comprising front, back and side frames, the front and back frames having par-

allel projections one above another at each of their lateral edges extending outward and downward, the side frames having on their inner faces at the front and rear matching recesses at the same inclination as said projections, into which the projections are inserted, a seat frame surrounded by the aforesaid frames, studs extending outward horizontally from the front of the seat frame, the front frame having recesses 10 on its inner face at the top to receive said studs, bolts engaging the side frames and seat frame and a transverse retaining rod passing through the back and side frames at the rear of the support.
